(57) **CLAIM**

The ornamental design for a shoe sole, as shown and described.

DESCRIPTION

FIG. 1 is a first perspective view of a shoe sole showing our new design;

FIG. 2 is a second perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a top view thereof.

The dot-dash-dot broken lines immediately adjacent the photographic areas represent unclaimed boundaries of the design. The broken lines form no part of the claimed design. Color forms no part of the claimed design.

1 Claim, 8 Drawing Sheets
